ION VON KERT HOTT, OF DAYTON, OHIO, ASSIGNOR TO THE JOYCE-CRIDLAND COMPANY,
OF DAYTON, OHIO, A CORPORATION OF OHIO

LIFTING MECHANISM

Application filed December 17, 1938. Serial No. 326,422.

This invention relates to a lifting mechanism and more particularly to an electrically operated mechanism for elevating an automobile to permit access to be had to the chassis thereof for the purpose of lubricating the same.

One object of the invention is to provide a simple but efficient lifting mechanism which will be of a compact arrangement and of a strong durable character.

A further object of the invention is to provide a lifting mechanism of this character in which the lifting element and its operating and controlling devices, with the exception 15 of the motor, will be supported within the outer casing.

A further object of the invention is to provide a lifting mechanism of this character having means for automatically interrupting 20 the operation of the motor when the lifting element reaches the limit of its movement.

Other objects of the invention will appear as the mechanism is described in detail.

In the accompanying drawings Fig. 1 is 25 a top plan view, partly broken away, of a lifting mechanism embodying my invention; Fig. 2 is a vertical sectional view taken on the line 2—2 of Fig. 1; Fig. 3 is a transverse sectional view taken on the line 3—3 of Fig. 30 2; Fig. 4 is a transverse sectional view taken on the line 4—4 of Fig. 2 and partly broken away; and Fig. 5 is a detail elevation of the circuit breakers and closers and the actuating device therefor.

35 In these drawings I have illustrated one embodiment of my invention but it will be understood that this particular embodiment has been chosen for the purpose of illustration only and that the mechanism may take 40 various forms and may be arranged in various ways without departing from the spirit of the invention.

In that form here illustrated the lifting mechanism comprises an outer casing adapted to be embedded in the ground with its upper end flush with the surface of the ground. As here shown, this casing comprises a base 6 on which is mounted a cylindrical shell 7 constituting the lower portion of the casing 50 and on the upper end of which is supported

the upper portion of the casing and which is preferably in the form of a casting 8. In practice this upper portion of the top casting of the casing is usually embedded in a slab of concrete with its upper end substantially flush with the upper surface of the concrete. The casing is provided with a bearing of less diameter than the casing and this bearing is here shown at 9 at the upper end of the top casting 8 and is eccentrically arranged 55 with relation to the casing.

Slidably mounted in the bearing 9 for vertical movement with relation to the casing, is a lifting element 10 which is preferably cylindrical in form and projects above the bearing. Rigidly secured to the upper end of the lifting element is a transverse frame member 11 on which are mounted two runways or tracks 12 to receive the wheels of the automobile which is to be elevated. The 60 lifting element 10 is carried by a supporting member 13 having its central portion screw threaded and constituting a nut, as shown at 14, which engages an actuating screw 15 rotatably mounted at its lower end in a bearing 16 in the base 6 of the casing. The supporting member 13 is here shown as substantially frusto-conical in shape and as having at its outer edge a circumferential recess 17 to receive the lower end of the cylindrical 65 lifting element and rotatably support the latter. The supporting member 13 is held against rotation and to this end may be provided with laterally extending lugs 18 arranged to engage the circumferential wall 70 of the outer casing 7. The screw 15 and nut 14 are of low pitch so that the screw will not rotate under the influence of the load on the nut but must be positively rotated in a reverse direction to lower the load.

Rigidly secured to the lower portion of the screw, below the thread thereof, is a gear 19 which is preferably of a diameter approximately equal to the diameter of the supporting member. An anti-friction bearing 20 is 75 preferably interposed between the gear and the base 6 of the casing to carry the weight of the load on the screw. A vertical shaft 21 is arranged in the outer casing between the circumferential wall thereof and the lifting 80

element and is supported at its lower end in a bearing 22 carried by the base 6 and is supported at its upper end in a bearing 23 carried by the top casting 8. Rigidly secured to this shaft near the lower end thereof and, if desired, formed integral therewith, is a pinion 24 which meshes with two idle gears 25 both of which mesh with the gear 19. At its upper end the shaft 21 is provided with a beveled gear 26 which meshes with a beveled gear 27 on a shaft 28 of a motor 29. The motor is of the reversible type and is provided with a master switch 30 for controlling the operation thereof.

15 Means are provided to automatically interrupt the operation of the motor as the lifting element approaches the limit of its movement in either direction, to prevent the nut from being run off the screw or the mechanism 20 injured in the event the operator should fail to actuate the master switch at the proper time. To this end two circuit breakers and closers 31 and 32 are interposed in the motor circuits, not shown, between the motor and 25 the master switch in such a manner that the circuit breaker and closer 31 will control the rotation of the motor in the direction to lower the load and the circuit breaker and closer 32 will control the rotation of the motor in 30 a direction to lift the load. These circuit breakers and closers are arranged within the casing and, as here shown, are mounted in a bracket 33 carried by the top casting 8. They may be of any suitable construction and are 35 illustrated as of a well known type which need not be described in detail, except to note that each circuit breaker and closer comprises a yieldable plunger 34 having a tapered nose. A vertically movable actuating member 35 40 controls the positions of the plungers of the circuit breakers and closers and for this purpose is provided with a projection 36 the upper and lower edges of which are inclined to engage the beveled noses of the respective 45 plungers. The shape and arrangement of the actuating device are such that when in its lowermost position, as shown in Fig. 5, the upper circuit breaker and closer will be opened, interrupting the downward movement 50 of the lifting element, and the circuit breaker and closer 32 will be closed to permit the motor to rotate in a direction to elevate the lifting element. The actuating device 35 is carried by a rod 37 arranged within the 55 outer casing 7 alongside of the lifting element and slidably supported at its lower end in a vertical socket 38 in the base 6 and supported at its upper end in a bearing bracket 39 within the top casting 8. Rigidly secured to this rod are flanged collars or stops 40 and 41, arranged respectively near the upper and lower ends thereof and in the path of a lug 42 carried by the supporting 60 member 13 and arranged between the two

stops. The arrangement of the stops is such that when the lifting element is moved to its lowermost position, as shown in Fig. 2, the lug 42 will engage the lower stop 41 and move the actuating member to its lower position, as shown in Fig. 5, which, as stated, interrupts the rotation of the motor in a direction to lower the lifting element. When the master switch is moved to the "up" position, see Fig. 1, the motor will be operated in a direction to elevate the lifting element and as the lifting element approaches the upper limit of its movement the lug 42 will engage the stop 40 and shift the actuating device to reverse the circuit breakers and closers, thereby interrupting the operation of the motor in a direction to elevate the lifting element. This upward movement of the actuating device also releases the plunger of the lower circuit breaker and closer 32 so that the motor circuit is in a condition to cause the motor to operate to lower the load when the master switch is again shifted. The actuating device may be retained in its elevated position during the downward movement of the lifting element by the contact thereof with the plunger of the lower circuit breaker and closer 32 but in order to relieve this plunger of a portion of the weight of a rod 37 I prefer to provide means for counterbalancing the weight of that rod. As here shown, this is done by interposing a light spring 43 between the bearing bracket 39 and the actuating device.

The lifting element is braced against tilting movement by means of a guide flange 44 extending inwardly from the wall of the top casting of the outer casing and extending about the lifting element for considerably more than half of its circumference, so as to brace the same against lateral movement in any direction. The ends of the flange 44 are spaced apart a distance sufficient to permit the passage of the shaft 21 and the rod 37.

While I have shown and described one embodiment of my invention I wish it to be understood that I do not desire to be limited to the details thereof as various modifications may occur to a person skilled in the art.

Having now fully described my invention, what I claim as new and desire to secure by Letters Patent, is:

1. In a lifting mechanism of the character described, a casing, an actuating screw rotatably mounted in said casing, a supporting member having a screw threaded part engaging said screw and held against rotation, a lifting element rotatably mounted on said supporting member, a shaft mounted in said casing alongside of said lifting element, a gear train connecting said shaft with said screw, and a motor connected with the upper end of said shaft.

2. In a lifting mechanism of the character described, a cylindrical casing having a bear-

ing near its upper end, said bearing being of less diameter than said casing and being arranged eccentrically with relation thereto, a cylindrical lifting element slidably mounted in said bearing, a nut having supporting connection with said lifting element and held against rotation, an actuating screw rotatably mounted in said casing and extending through said nut, a vertical shaft mounted in said casing at one side of said lifting element, gearing connecting said shaft with said screw, an electric motor connected with said shaft, a circuit breaker and closer for said motor, an actuating device for said circuit breaker and closer comprising a rod mounted for vertical movement in said casing at one side of said lifting element, a stop carried by said rod, and a part carried by said nut and engaging said stop to impart operative movement to said actuating device.

3. In a lifting mechanism of the character described, a cylindrical casing having a bearing near its upper end, said bearing being of less diameter than said casing and being arranged eccentrically with relation thereto, a cylindrical lifting element slidably mounted in said bearing, a nut having supporting connection with said lifting element and held against rotation, an actuating screw rotatably mounted in said casing and extending through said nut, a vertical shaft mounted in said casing at one side of said lifting element, gearing connecting said shaft with said screw, an electric motor connected with said shaft, a pair of circuit breakers and closers for said motor arranged one above the other and each comprising a yieldable plunger, a rod mounted for vertical movement in said casing at one side of said lifting element, an actuating device carried by said rod and having inclined edges to engage the plungers of the respective circuit breakers and closers, stops carried by said rod and spaced apart, a part carried by said nut and arranged between said stops to impart lengthwise movement to said rod when said lifting element approaches either limit of its movement, and means for counterbalancing the weight of said rod and said actuating device.

4. In a lifting mechanism of the character described, a casing comprising a base, a cylindrical shell carried by said base, and a top casting carried by said shell and having a bearing of less diameter than said shell, an actuating screw rotatably supported on said base, a nut mounted on said screw and having a circumferential portion, a cylindrical lifting element rotatably supported on the circumferential portion of said nut and slidably mounted in said bearing, a gear secured to said screw below the threaded portion thereof, a vertical shaft mounted in said casing alongside of said lifting element, a gear train for connecting said shaft with the first men-

tioned gear, and a motor connected with said shaft.

5. In a lifting mechanism of the character described, a substantially cylindrical casing adapted to be embedded in the ground with its upper end adjacent to the surface of the ground, said casing having near its upper end a bearing of less diameter than the body of said casing, a lifting element mounted for vertical movement in said bearing, a nut connected with said lifting element and held against rotation, an actuating screw rotatably mounted in the lower portion of said casing and having threaded engagement with said nut, a vertical operating shaft mounted in said casing and alongside of said lifting element, gearing connecting said shaft with said screw below said lifting element, and means connected with said shaft near the upper end of said casing for rotating the same.

6. In a lifting mechanism of the character described, a substantially cylindrical casing adapted to be embedded in the ground with its upper end adjacent to the surface of the ground, said casing having near its upper end a bearing of less diameter than the body of said casing, a lifting element mounted for vertical movement in said bearing, a nut connected with said lifting element and held against rotation, an actuating screw rotatably mounted in the lower portion of said casing and having threaded engagement with said nut, a vertical operating shaft mounted in said casing and alongside of said lifting element, gearing connecting said shaft with said screw below said lifting element, means connected with said shaft near the upper end of said casing for rotating the same, and means within said casing and controlled by the movement of said lifting element to interrupt the rotation of said shaft when said lifting element reaches the limit of its movement in one direction.

7. In a lifting mechanism of the character described, a substantially cylindrical casing adapted to be embedded in the ground with its upper end adjacent to the surface of the ground, said casing having near its upper end a bearing of less diameter than the body of said casing, a lifting element mounted for vertical movement in said bearing, a nut connected with said lifting element and held against rotation, an actuating screw rotatably mounted in the lower portion of said casing and having threaded engagement with said nut, a vertical operating shaft mounted in said casing and alongside of said lifting element, gearing connecting said shaft with said screw below said lifting element, a motor having driving connection with said shaft, a circuit breaker and closer connected with said motor, a rod mounted for longitudinal movement in said casing and extending lengthwise of said lifting element, means carried by said rod for actuating said circuit breaker.

- and closer, and a part movable with said lifting element to impart longitudinal movement to said rod when said lifting element approaches the limit of its movement in one direction. 5
8. In a lifting mechanism of the character described, a substantially cylindrical casing, an actuating screw rotatably mounted in said casing on an axis arranged eccentrically with relation to said casing, a supporting member having a screw threaded part engaging said screw and having a part engaging said casing to hold said member against rotation, a lifting element carried by said supporting member, a vertical shaft mounted in said casing alongside of said lifting element, gearing connecting the lower portion of said shaft with said screw, and a motor connected with said shaft near the upper end of said casing. 15
9. In a lifting mechanism of the character described, a substantially cylindrical casing, an actuating screw rotatably mounted in said casing on an axis arranged eccentrically with relation to said casing, a supporting member having a screw threaded part engaging said screw and having a part engaging said casing to hold said member against rotation, a lifting element carried by said supporting member, a gear secured to said screw, a shaft 20 rotatably mounted in the lower portion of said casing and extending upwardly between the wall of said casing and said lifting element to a point near the top of said casing, a pinion carried by said shaft near the lower 25 end thereof, intermediate gearing connecting said pinion with the first mentioned gear, and a motor connected with the upper end of said shaft. 30
10. In a lifting mechanism of the character described, a substantially cylindrical casing having a bearing near its upper end, said bearing being of less diameter than said casing and being arranged eccentrically with relation thereto, a cylindrical lifting element 35 slidably mounted in said bearing, a nut having supporting connection with said lifting element and held against rotation, an actuating screw mounted in said casing and extending through said nut, a vertical shaft rotatably mounted in the lower portion of said 40 casing and extending upwardly between said casing and said lifting element, gearing connecting the lower end of said shaft with said screw, and a motor connected with the upper end of said shaft. 45
11. In a lifting mechanism of the character described, a cylindrical casing having a bearing near its upper end, said bearing being of less diameter than said casing and being arranged eccentrically with relation thereto, a cylindrical lifting element slidably mounted 50 in said bearing, a nut having supporting connection with said lifting element and having laterally extending lugs to engage the cylindrical wall of said casing and hold said nut 55
- against rotation, an actuating screw rotatably mounted in said casing and extending through said nut, a vertical shaft rotatably mounted in the lower portion of said casing and extending upwardly between said casing 70 and said lifting element to a point near the top of said casing, gearing connected with the lower end of said shaft, and a motor connected with the upper end of said shaft. 75
